UNITED STATES PATENT OFFICE.

JACK CLARK, OF ROSEDALE, NEW YORK.

GOLF TEE.

Application filed October 27, 1925. Serial No. 65,215.

This invention relates to that class of devices used in the game of golf in which a ball is struck by a club causing the ball to travel in a predetermined direction over variably long or short distances.

In order to enable the ball to be properly struck by the club, while teeing off, it is customary to raise the ball off the ground on a tee in order to prevent the lower portion of the golf club face dragging in the ground, thereby retarding the speed of the club and throwing the club out of alignment, and upsetting the travel of the ball by causing top or side spin, resulting in hooks and slices.

Various tees of both metallic and fibrous substances have been used for such teeing purposes; but the metallic ones are objectionable on a golf course, while the present fibrous and wooden ones break too easily. Also all of the tees as now in use must either be pushed into the ground so far to give the tee proper support, that the club strikes the ground, particularly with the use of the deeper faced clubs, or if the present tees are not so pushed into the ground, the aforementioned difficulty is overcome, but then, when the ball is placed thereon, they are top heavy causing them to topple. This is particularly so in a high wind or in sandy soil. Also, when grounding the club, while addressing the ball on such a tee, the least give of the earth causes the tee to topple under the weight of the ball.

The main object of this invention is to provide a one-piece golf tee, which is simply manufactured of wood, pulp or paper at a low cost, which will be adequately supported by a simple pushing into the ground and which will raise the ball to the height required to get sufficient carry to the ball.

A further object of the invention is to provide a substantial tee, which may be used over and over again, because of its rigid construction and ease of withdrawal from the ground.

The invention is shown in the accompanying drawing, which is made a part of this application. The complete tee is as shown and consists of a cylinder B essentially of the shape shown with the upper face A thereof dished slightly to receive the golf ball. In order to prevent the club in its swing from striking the tee with too great a force the surface of the cylinder B is recessed in the curve EBC. From the bottom

face C of the cylinder extends the shank D of a slight taper and with fillets at the face C, as shown, and pointed at the opposite end for facility in inserting into the ground.

The herein described golfing tee is made of wood by turning or otherwise, but may be made of suitable compositions by moulding or pressing to the shape shown. The tee is made one-half the size of the drawing and hence is inexpensive in its manufacture.

From the description of the herein golf tee, it is evident that when inserting the tee into the ground, a simple push is required, and an automatic stop provided by the shoulder C. The ball is, therefore, always at the predetermined height necessary to give it the proper carry for the present day straight and deep faced wooden club.

When putting the golf ball on the tee, this tee eliminates the top heaviness incidental to other tees due to the support given by the shoulder C in combination with the shank D.

When striking the ball, the ball is first struck and the tee merely grazed. Even if the tee is struck forcibly the construction thereof is rigid enough to prevent breakage to any great extent, thus enabling the continued use of the tee. Further, when the tee is hit, it will not fly from its position, necessitating a search therefor; rather the shoulder of the tee will bury itself into the soil and the tee remain where it is.

In withdrawing the tee a grip is furnished by the shoulder E, together with the receding surface TRC enabling its easy withdrawal from the ground.

What I claim is:

1. A golf tee made of rigid material, comprising a body portion having a top shaped so as to hold a golf ball in a fixed position, said body portion having also a downwardly and outwardly flared shoulder beneath the said top located at a level to position the body portion of the tee against the surface of the ground so that the upper surface of said shoulder is adapted to act as a brake with the ground, and a shank extending downwardly from said shoulder to be inserted into the ground.

2. A one-piece golf tee made of rigid material, comprising a body portion having a top shaped so as to hold a golf ball in a fixed position, said body portion having also a downwardly and outwardly flared

shoulder beneath the said top located at a level to position the body portion of the tee against the surface of the ground so that the upper surface of said shoulder is adapted to act as a brake with the ground, and a shank extending downwardly from said shoulder to be inserted into the ground.

3. A golf tee made of rigid material, comprising a body portion having a top shaped so as to hold a golf ball in a fixed position, said body portion having also a downwardly and outwardly flared shoulder with a tapered underface beneath the same located at a level to position the body portion of the tee in an upright position against the surface of the ground so that the upper surface of said shoulder is adapted to act as a brake with the ground, and a shank ex-

tending downwardly from said shoulder to be inserted into the ground.

4. A one-piece golf tee made of rigid material comprising a body portion having a top shaped so as to hold a golf ball in a fixed position said body portion having also a downwardly and outwardly flared shoulder with a tapered underface beneath the said top located at a level to position the body portion of the tee in an upright position against the surface of the ground so that the upper surface of said shoulder is adapted to act as a brake with the ground, and a shank extending downwardly from said shoulder to be inserted into the ground.

In testimony whereof I affix my signature this 13th day of October, 1925.

JACK CLARK.
